Inventor:
Alexander Webster.
By: Gabel, Mueller Atts.

UNITED STATES PATENT OFFICE.

ALEXANDER WEBSTER, OF CHICAGO, ILLINOIS.

COMBINATION TIE AND COLLAR.

Application filed October 5, 1922. Serial No. 592,548.

My invention relates to combination ties and collars, and has to do more particularly with the provision of a one-piece tie and collar adapted for attachment to shirts, being directed more particularly to an article in which the tie portions extend from the ends of the collar at the front and are shaped so as to be formed into a tie, such as a bow tie or a four-in-hand tie.

10 For a better understanding of my invention reference is to be had to the accompanying drawing, in which—

Fig. 1 shows the ordinary soft turn-down collar with the tie portions attached directly thereto or extending therefrom;

Fig. 2 shows the collar and tie of Fig. 1 with the tie formed up;

Fig. 3 shows a collar with the tie shaped up as a four-in-hand tie, and

20 Fig. 4 shows a portion of a collar with a tie portion extending therefrom and indicated as of a material different than the collar.

Referring now more in detail to the form 25 of my invention as shown in Figs. 1 and 2, I have illustrated a detachable collar comprising the inner or attaching portion 5, and the outer or turn-down portion 6. In this form of my invention the tie portions 7 and 8 are preferably of self-material, that is, of material the same as the collar, and extend outwardly as a continuation of the collar cloth. The tie portions 7 and 8 are preferably slightly narrower at the meeting points 30 9 and 10, so that the tie may be more readily formed.

In Fig. 2 the tie is shown as being formed up as a bow tie.

In Fig. 3 I have shown the collar 5' as being attached directly to a shirt 11, that is, permanently attached as is usual with soft shirts. The tie in this form of my invention is shown as a four-in-hand, but it will be apparent that either type of tie may be used, 45 as desired.

In using the detachable collar such as is shown in Figs. 1 and 2, the tie and collar may of course be laundered separately from the shirt, as is customary now with the soft 50 collars in general use.

In the form of invention shown in Fig. 3, that is, with the collar permanently attached

to the shirt, the entire article is of course always permanently connected.

In Fig. 4 I have shown the tie as being of 55 a different material than the collar, in which case of course the tie is suitably attached to the outer or turndown flap of the collar. It will be apparent that various combinations may be used in this way and the collar and 60 tie be made up of self-material to match the shirt, or of a suitable white or other material. Also it is to be understood that the collar and tie may be made up in various ways so that the collar may be laundered as 65 the usual stiff collar but the tie may be left soft so that it may be readily formed up as desired.

Although I have illustrated my invention in several different ways, I contemplate making it up in other ways than that shown, and understand that changes and modifications will readily occur to those skilled in the art.

Therefore, I do not desire to be limited to the structures shown and described but 75 aim to cover all that which comes within the spirit and scope of the appended claim.

What I claim as new and desire to secure by United States Letters Patent, is:—

A combined collar and necktie including 80 a collar to be worn about the neck and attached to the usual shirt collar band and having inner and outer portions, the outer portion having straight ends spaced to afford an opening at the front of the collar 85 of sufficient size to neatly accommodate the knot of the necktie, and a tie strand carried by each end of the outer portion from a point centrally of the upper and lower edges thereof and being considerably narrower at 90 their attached ends than the straight ends of the outer portion and arranged to be tied together to form a tie with the knot of the latter accommodated in the opening centrally of the upper and lower edges of the 95 outer portion, whereby they are drawn and retained against the shirt band and the straight edges above and below the tie exposed to view.

In witness whereof, I hereunto subscribe 100 my name this 26th day of September A. D., 1922.

ALEXANDER WEBSTER.
